Primary Examiner — Cynthia Underwood(74) *Attorney, Agent, or Firm* — Law Offices of S.J. Christine Yang(57) **CLAIM**

The ornamental design for an automotive wheel lug nut, as shown and described.

DESCRIPTION

FIG. 1 is a perspective view of the automotive wheel lug nut showing my new design;

FIG. 2 is a side view of FIG. 1;

FIG. 3 is a bottom view thereof; and,

FIG. 4 is a top view thereof.

The broken lines and that within the broken lines represent environment and form no part of the claim.
